UNITED STATES PATENT OFFICE

155,834

DESIGN FOR A MILK BOTTLE

Michael A. Pecora, West Hazleton, Pa., assignor
to Pecora's Farm Dairy, West Hazleton, Pa., a
partnership

Application September 3, 1948, Serial No. 148,460

Term of patent 14 years

(Cl. D58—9)

To all whom it may concern:

Be it known that I, Michael A. Pecora, a citizen of the United States, residing at West Hazleton, in the county of Luzerne and State of Pennsylvania, have invented a new, original, and ornamental Design for Milk Bottles, of which the following is a specification, reference being had to the accompanying drawing, forming part thereof.

Figure 1 is a side elevational view of a milk bottle, showing my new design.

Figure 2 is a front elevational view of the bottle.

I claim:

The ornamental design for a milk bottle, as shown.

MICHAEL A. PECORA.
